UNITED STATES PATENT OFFICE.

FRANK SCHREIDT, OF MANSFIELD, OHIO.

COMBINED HOLDER AND FEEDING DEVICE FOR BRUSHES.

1,118,687.

Specification of Letters Patent.

Patented Nov. 24, 1914.

Application filed August 5, 1913. Serial No. 783,064.

To all whom it may concern:

Be it known that I, FRANK SCHREIDT, a citizen of the United States of America, residing at Mansfield, in the county of Rich-
5 land and State of Ohio, have invented cer-
tain new and useful Improvements in a
Combined Holder and Feeding Device for
Brushes, of which the following is a speci-
fication.

10 This invention relates to certain new and useful improvements in fountain brushes, and pertains more particularly to brushes, such as tooth and shaving, which are used with paste commonly provided in tubes.

15 The primary object of the invention is to provide means in connection with a brush whereby paste may be applied to the bristles thereof without waste of the paste.

More specifically, the invention aims to 20 provide, in its preferred form, a casing which encircles and incloses the brush bristles, and which has means for connection with the threaded neck of a tube of paste, whereby the paste may be fed, in regulable
25 quantities, to the bristles.

Further, the invention aims to provide a 30 casing which is sanitary, and at all times has a supply of paste, enabling the casing to be easily and quickly applied to the brush bristles, and paste fed thereto, in a manner later set forth herein, in detail.

In the drawings: the figure is a side elevation of the invention partly in section.

The drawing indicates a shaving brush 35 which may be of any type, since it forms no part of the present invention.

The invention includes a casing 1 prefer-
ably formed with a knurled portion 2, so as
to permit operation without slippage in the
40 hand of the user. As depicted in the draw-
ings, the casing is of such size and shape as
to receive the brush bristles, and to also en-
gage over the shank S of the brush so as to
hold the casing stationary relative to the
45 brush. The outer end of the casing is open
while its inner end is closed, as indicated at
3 so as to contact with the free ends of the
bristles. The closed end 3 is formed with
a paste inlet 4 and with an interiorly thread-
50 ed outwardly projecting neck 5 which is
adapted to threadedly engage the exteriorly

threaded neck N of the tube of paste P,
which latter is of the usual commercially
known type of collapsible tube form.

In operation, the neck N of the tube of 55
paste P is threaded into engagement with the
neck of the casing, so as to form a connection
between the two which connection is main-
tained until the tube is empty, whereupon
a new tube filled with paste is substituted. 60
The casing 1, is placed over the bristles and
engaged with the shank S of the brush,
whereupon, by squeezing the tube P, the
desired amount of paste is fed to the brush
bristles, after which the casing is removed 65
from the brush.

From the above it will be evident that the
invention contemplates application of tubes
of shaving cream, paste or powder, or tooth
cream, paste or powder to brushes, for the 70
particular purpose mentioned, so that the
substance employed can be easily, quickly,
effectively, and regulably fed to the brush
bristles.

What is claimed is:—

1. A casing for attachment to a brush and
adapted to encircle and inclose the brush
bristles, said casing having a paste inlet,
and a separate collapsible tube containing
paste attached to the casing to communi- 80
cate with the paste inlet to feed paste
thereto.

2. A device of the type set forth, includ-
ing a casing adapted to inclose the bristles
of a brush and having a paste inlet and 85
means by which an independent tube of
paste may be attached to the exterior of the
casing so that collapsing of the tube will
feed the paste to the inlet.

3. In a device of the type set forth, a 90
casing adapted to encircle the brush bristles
and having a closed end provided with an
inlet, and an interiorly threaded neck on the
casing the interior of which communicates
with said inlet, said neck being adapted to 95
receive the exteriorly threaded neck of a
separate collapsible tube of paste or the
like.

4. In a device of the type set forth, a
casing having an inlet at one end and hav- 100
ing its opposite end open to receive the bris-
tles of a brush therein, the extreme portion

of said open end of the casing being adapted to grip the shank of the brush handle, and means by which an independent collapsible tube containing paste may be attached to said first named end of the casing whereby collapsing of the tube will feed paste to said inlet.

In testimony whereof I affix my signature in presence of two witnesses.

FRANK SCHREIDT.
